UNITED STATES PATENT OFFICE.

FRANK E. FRISBEE, OF DES MOINES, IOWA.

WINDOW-FRAME.

1,076,567.

Specification of Letters Patent. Patented Oct. 21, 1913.

Application filed February 26, 1912. Serial No. 680,123.

To all whom it may concern:

Be it known that I, FRANK E. FRISBEE, a citizen of the United States, residing at Des Moines, in the county of Polk and State of Iowa, have invented a certain new and useful Improvement in Window-Frames, of which the following is a specification.

The object of my invention is to provide a window frame of simple, durable and inexpensive construction in which the parts that come in contact with the sliding sashes are made wholly of sheet metal in a strong and durable manner and also so that they may be readily and easily applied to a building.

My object is further to provide a window frame of this class with adjustable stops so arranged that the operator may readily and easily cause the stops to withdraw into the interior of the frame to thereby leave the surface of the frame unobstructed, thus permitting the window sashes to move freely in and out of the window frame so that they may be easily and quickly cleaned.

A further object is to provide means for adjusting the stops so that they may be made to bear upon the sashes with any desired amount of pressure and so that the swelling or contracting of the wood in the sashes may be compensated for and the sashes may be made so that they will slide up or down with any desired amount of friction or so that the sashes may be both forced firmly against the central stop and against each other to make tight joints.

A further object is to provide improved means for locking the stops in any position of their adjustment so that the amount of pressure applied by the stops to the window sashes will remain constant at the point at which the locking device is fixed.

My invention consists in certain details, in the construction, arrangement and combination of the various parts of the device, whereby the objects contemplated are attained, as hereinafter more fully set forth, pointed out in my claims and illustrated in the accompanying drawings, in which:

Figure 1 shows a vertical, transverse, sectional view through a window frame and window sashes embodying my invention. Fig. 2 shows an enlarged, detail view illustrating a part of a window frame provided with my improvement showing the inside of the frame. Fig. 3 shows an enlarged detail, sectional view on the line 3-3 of

Fig. 2. Fig. 4 shows a sectional view through the top of the window frame. Fig. 5 shows a detail, sectional view through one of the movable stops to show the links by which the stops are moved in and out. Fig. 6 shows a detail view illustrating the spring for holding the locking device in any position in which it may be adjusted, and Fig. 7 shows a detail view illustrating the locking plate.

Referring to the accompanying drawings, my improved frame is seen to be composed of a number of smooth flat boards 10 which are first placed in position instead of the ordinary window frames which are usually provided with grooves and parting stops, said boards being extended over the sides and top of the frame.

On the inner surface of the board 10 on the sides of the frame, I first place a flat sheet metal strip 11 having its ends bent at right angles over the ends of the board 10. Secured to this sheet metal strip 11 is another strip of sheet metal comprising an outer end portion 12 secured to and overlapping the end of the metal strip 11 and a number of straight portions 13 spaced apart from the strip 11 and having between them the grooved portions 14, there being preferably three of said grooved portions. The inner parts of said grooved portions are connected to the part 11 by rivets 15, thus firmly and securely uniting the two metal strips and holding the parts 13 accurately spaced apart from the sheet metal strip 11.

In each of the grooves 14 is a parting stop; the central one is made of a single piece of sheet metal and comprises two parallel sides 16 and a straight central portion 17 at right angles to the sides. This parting stop is of such size and shape as to be capable of sliding into the groove 14 so that its outer portion 17 is flush with the straight portions 13 and it is also capable of being projected outwardly from the straight portions 13 to form parting stops for the window sashes 18. The parting stop in the outer groove 14 has its inner side beveled at 19, as shown in Fig. 3, and the inner parting stop has its outer side beveled at 20, as shown in Fig. 3. These beveled portions are designed to engage the inner surface of the lower sash and the outer surface of the upper sash and when said parting stops are in their extended positions the beveled portions tend to hold the two sashes firmly to-

ward each other and against the central parting stop, and when the parting stops are all moved outwardly a short distance so that they are only partially inserted in their respective grooves, the beveled portions will permit the sashes to freely slide between the parting stops. By this means the parting stops may be made to engage the sashes in such a manner as to tightly 10 hold them against the central parting stop and against each other so that they may be adjusted and the sashes slide freely and loosely between them. As shown in Fig. 5 the parting stops are shorter than the grooves in the 15 frame in order to permit the sliding movement of the stops.

In order to provide for jointly moving the parting stops in and out, I have pivoted on the interior of each parting stop an arm 21 20 extended toward the metal strip 11. The lower one is provided with a square opening 22 and the upper one is provided with a pivot pin 23 which connects it with the part of the sheet metal strip that forms the 25 groove 14. For convenience in assembling these arms 21, I preferably provide an inwardly extending lug 24 on the material at the bottom of the groove 14 on which the arm 21 may rest when being assembled. 30 In order to connect all of the lower arms 21 together so that they may be jointly moved, I provide a square shaft 25 which is extended through the parts of the material that forms the groove 14 and also 35 through the square openings 22 of the arms 21. This shaft turns freely in the openings through the parts forming the grooves 14 and when turned it will jointly move all of the lower arms 21, the limit of movement 40 being from the horizontal position shown in Fig. 5 to a substantially vertical position with the parting stops wholly received into the grooves.

Under certain conditions it is possible the 45 when the parting stops are in position to firmly engage the window sashes vertical movement of the window sashes might tend to move the parting stops either up or down and thus cause them to tighten or loosen 50 relative to the sashes. In order to prevent this and for the purpose of locking the parting stops in any position in which they are placed, I have provided on one end of the shaft 25 an extensible coil spring 26 de- 55 signed to move the shaft 25 longitudinally toward the outer side of the window frame. On the inner end of the shaft 25, I have provided a locking plate 27 provided with a series of notches 28. This plate is de- 60 signed to be secured to the inner surface of the window frame as shown in Fig. 2. Mounted upon the shaft 25 is an arm 29 having a lug 30 thereon, which lug is de- 65 signed to enter the notches 28 on the plate 27. A crank 31 is detachably connected to

the inner end of the shaft 25 so that the said shaft may be readily and easily turned, and obviously when turned to another position it will be yieldingly held by the spring 26 holding the lug 30 in one of the 70 notches 28.

The top portion of the window frame, as clearly shown in Fig. 4, comprises a sheet metal strip 32 fixed to the board 33 which forms the top of the window frame. This 75 metal strip 32 is provided with a single parting stop 34 formed in the material.

In order that the upper window sash may be firmly held against the parting stop 34, I have provided a metal strip 35 having a 80 substantially U-shaped rib 36 formed at one edge, the free end of which is designed to rest against the upper sash so that it will yieldingly hold the sash against the strip 34. The material of which the U-shaped 85 rib is formed is sufficiently resilient to allow for the ordinary contraction and expansion of the wooden sash so that a tight joint will be made at the top of the window sash under all ordinary conditions, thus dispensing 90 with the necessity of making adjustable stops for the top of the sash.

One of the advantages of my invention is that the sides of the frame are made up of 95 two pieces of sheet metal which may be readily and easily pressed or rolled into the desired shape without hand work and at slight expense. The metal need not be heavy for the reason that the two pieces are united by rivets at several points, thus bracing 100 and supporting each other. These metal frame members may be connected to a window by first placing in the window opening a frame of straight flat boards 10 and the metal parts may be connected to these boards 105 very readily and easily, or the entire metal frame may be placed in any ordinary window frame and the sashes fitted thereto by simply cutting off about one half an inch of 110 the edge of the window. Another advantage 115 is that the sheet metal parting stops are arranged for movement within the grooves formed in the sheet metal frame members so that when the parting stops are moved 120 they will slide readily and easily.

The construction by which the two beveled parting stops may be made to force the sashes firmly against the central parting stop and against each other is of considerable importance. Furthermore the construction 125 by which the parting stops may be locked in any position of their adjustment is advantageous for the reason that the sashes may be made to slide freely and easily regardless of the construction or expansion of the 130 wooden sashes and if under certain conditions the sashes do not slide freely the operator need only turn the shaft 25 a part of a revolution, whereupon the pressure on one side of each sash is removed, or if the sashes 135

do not fit tightly enough the shaft 25 may be turned in the opposite direction and the sashes will be firmly held against the central parting stop.

5 I claim as my invention:

1. In a window frame, the combination of a sheet metal strip, a second sheet metal strip with its body portion spaced apart from the first and with its edges connected 10 to the edges of the first, said second strip being formed with a number of longitudinally arranged grooves, the material at the bottom of the grooves being fixed to the material of the first strip, a series of parting 15 stops mounted in said grooves, each parting stop being provided with arms pivotally connected to it, the upper arms being also pivoted within the grooves and the lower arms being connected to a shaft, said shaft 20 having its bearings in the sides of the material that forms said grooves, an arm carried by said shaft and provided with a lug, a plate fixed to the window frame and having notches designed to be engaged by said 25 lug, and a spring for yieldingly holding the shaft in position so that the lug engages said notches.

2. In a window frame, the combination of a flat sheet metal strip having its edges arranged at right angles, a second sheet metal strip formed with three longitudinally arranged grooves, the material at the bottom portions of said grooves being in engagement with the first strip and being firmly fixed thereto, the material at the bottoms of 30 said grooves being also provided with inwardly extending lugs, a series of parting stops mounted in said grooves and each comprising a substantially U-shaped sheet metal body portion, a series of links pivoted within said parting stops at one end, their other ends being rested on the said lugs, the upper links being pivoted to the material which forms the grooves and the lower links 35 being formed with square openings, a shaft extended through the square openings of the lower links and also extended through the sides of the material forming said grooves, and means for turning said shaft.

Des Moines, Iowa, January 17, 1912.

FRANK E. FRISBEE.
